CLAIM

The ornamental design for a doorbell, as shown and described.

DESCRIPTION

FIG. 1 is a front perspective view of a doorbell showing our new design;

FIG. 2 is a rear perspective view thereof;

FIG. 3 is a front elevational view thereof;

FIG. 4 is a rear elevational view thereof;

FIG. 5 is a right-side elevational view thereof;

FIG. 6 is a left-side elevational view thereof;

FIG. 7 is a top plan view thereof; and,

FIG. 8 is a bottom plan view thereof.

The broken lines immediately adjacent the shaded areas represent bounds of the claimed design while all other broken lines depict portions of the doorbell that form no part of the claimed design; the broken lines form no part of the claimed design.

1 Claim, 7 Drawing Sheets
